UNITED STATES PATENT OFFICE.

EARL P. OSWALD, OF DETROIT, MICHIGAN, ASSIGNOR TO UTILITY COMPRESSOR COMPANY, A CORPORATION OF MICHIGAN.

FLUID COMPRESSOR.

Application filed July 15, 1920. Serial No. 396,477.

To all whom it may concern:

Be it known that I, EARL P. OSWALD, a citizen of the United States, residing at Detroit, county of Wayne, State of Michigan, 5 have invented a certain new and useful Improvement in Fluid Compressors, and declare the following to be a full, clear, and exact description of the same, such as will enable others skilled in the art to which it pertains to make and use the same, reference being had to the accompanying drawings, which form a part of this specification.

This invention relates to fluid compressors, and the object is to provide a fluid compressor of very simple construction that is automatically relieved of the load imposed by the high pressure line upon cessation of operation and in which the load is not assumed by the compressor at the instant of 10 starting whereby the compressor may be directly connected with an electric motor or other operating means enabling the motor to attain its speed of operation prior to the assumption of the load by the compressor. 15 A further object is to provide a fluid compressor of a character and construction permitting the pistons to be so set in the cylinders that the entire contents of each of the cylinders is discharged on each stroke of 20 the piston.

Generally with fluid compressors a clearance space is necessarily provided to prevent what is known as a "pound" of the pistons in the cylinders, and this clearance 25 space being filled with compressed fluid reduces the efficiency of the compressor inasmuch as the fluid under compression in the clearance space will, on the intake stroke of the piston, expand with the piston and no 30 new fluid is drawn into the cylinder until the pressure therein is below that of the intake side of the system. By providing a construction and mechanism eliminating the necessity of providing an appreciable clearance, the efficiency of the compressor is 35 greatly increased as is hereinafter more fully pointed out.

A further object of this invention is to provide a fluid compressor having cylinders 40 rotating about a center and reciprocable pistons therein connected at the outer ends to a member rotating with the pistons about an axis eccentric to the axis of rotation of the pistons, the object being to secure a smoothness of operation dispensing with cranks of 45

the usual type and causing the pistons to successively take in, compress and discharge a compressible fluid.

The compressor may be used for various purposes as for instance in the circulating system of artificial refrigerating plants having a high and low pressure side, the compressors taking the refrigerant, as sulphur dioxide, from the expansion side of the system and discharging it under pressure to 60 the compression or high pressure side of the system. An object of this invention is to dispense with the usual poppet type valves which are apt to become corroded or non-operative for various causes and to provide 65 a central valve plate with which the intake and discharge ends of the cylinders ride in contact when in operation, the plate having what I have termed ports with which the ports of the cylinders register successively during a revolution of the cylinders as hereinafter more fully described. A further feature of this invention is to provide 70 a construction whereby the cylinder ends are moved into contact with the valve plate 75 subsequent to attainment of certain predetermined speed of revolution of the cylinders and move away from the plate upon the speed decreasing below a certain predetermined speed of revolution thus automatically 80 connecting and disconnecting the compressor cylinders with the valve plate. By this arrangement an object of this invention is attained—namely, to secure an automatic loading and unloading arrangement whereby 85 the compressor may be directly connected with an electric motor. These and other objects and the several novel features of the invention are hereinafter more fully described and claimed, and the preferred form 90 of construction embodying my invention is shown in the accompanying drawings in which—

Fig. 1 is a vertical section of a fluid compressor and operating means therefor embodying my invention.

Fig. 2 is a section taken on line 2—2 of Fig. 1 showing the relationship of the cylinders and operating means for the pistons.

Fig. 3 is a face view of the valve plate 105 being a section taken on line 3—3 of Fig. 1.

Fig. 4 is a section taken on line 4—4 of Fig. 2 showing the intake and exhaust conduits opening through the valve plate to the compressor cylinders.

Fig. 5 is a detail showing a portion of the piston driving member showing a pin providing a driving means between the cylinder and the piston operating device.

5 As heretofore stated, the compressor consists of a series of cylinders which are arranged in a radial relation having the intake and discharge ends at the center and are revoluble about a common axis. The 10 relationship of the cylinders 1, 2 and 3 is shown in Fig. 2. These cylinders are preferably formed integrally in a single casting keyed to the central shaft 4. The upper face of the casting at the cylinder ends 15 is provided with a coned recess 5 in which are apertures 6, 7 and 8 for the respective cylinders. These apertures provide both the exhaust and intake channels which open directly into the end of the cylinders as shown 20 particularly in Fig. 1. The piston 9 of the cylinder 3 for instance may sweep the entire contents of the cylinder out through the exhaust aperture 8 due to the position of the said aperture and the same is true of the 25 other cylinders of the series. Each of the pistons of the cylinders is connected by means of a connecting rod 10 with the piston operating member 11. These piston rods may be of any approved type preferably 30 provided with a ball end 12 positioned in the operating member 11 in a manner to permit adjustment thereof longitudinally of the cylinders. This adjustment may be provided by the apertured inner screw member 35 13 through which the rod 10 extends and the inner end of which is provided with a seat for the ball. The screw 14 in the outer face of the operating member 11 is provided with a half seat for the said ball 12 in each 40 case and is complementary to the member 13 and, by threading these members 13 and 14 in or out relative to the longitudinal axis of the respective cylinder, the position of the piston may be adjusted with nicety permitting 45 the piston to be so set as to actually engage the cylinder end upon the exhaust stroke and thus discharge the entire contents of the cylinder.

In order that the pistons may have the 50 necessary reciprocable movement in the cylinders the operating member 11 is mounted on an axis indicated at *b* in Fig. 1 while the cylinders are mounted to turn on the axis indicated at *a* in Fig. 1 in eccentric relation to the axis of the piston operating member. The shaft 4 on which the cylinder casting is secured passes upward through a block 15 having a lower cone shaped end 16 complementary to the coned recess 5 of the 55 cylinder casting and, as hereinafter shown, is provided with intake and exhaust channels for the cylinders. This block 15, hereinafter termed a valve plate or block, is stationary and is provided with a circular portion 17, the center of which is eccentric to

the axis of the shaft passing through the block and providing a bearing for the hub portion 18 of the piston operating member. This block is of hardened steel providing bearing surface of long life for the part 18 70 of the piston operating member and for the cone part 16 and the coned portion 5 of the cylinder member and the faces of the bearing portions are carefully finished so that the coned portions may ride in perfect contact without possibility of leakage of air or gas therebetween. 75

The block 15 is secured in a frame member 19 and the piston operating member is held in position shown particularly in 80 Fig. 1 by a stirrup 90 which is U shaped in form secured at the ends to the opposite side of the frame 19, the horizontal portion of which, as is shown in Fig. 1 is apertured and provided with a bushing 91 forming a 85 bearing for the stub shaft 92 with which the member 11 is provided on the lower side. The axis of this shaft 92 coincides with the axis of the cylindrical portion 17 of the block 15 about which the member 11 revolves as hereinafter shown. 90

In the construction shown the casing 19 forms a part of a casing for an electric motor, the rotor and stator of which are indicated diagrammatically at 93 and 94. The 95 rotor shaft 4 extends upward and is provided with a bearing 95 at the upper end of the frame 19. A thrust bearing 26 is provided at the upper end of the block 15 which is engaged by a block 27 on the shaft to 100 which are pivoted the fly balls 28. A hardened steel washer 29 is provided at the lower end of the rotor which bears directly upon the upper ends of the levers 30 of the fly balls which are so shaped that, when the fly 105 balls are in position shown in Fig. 1 when the motor is idle, the compressor cylinders are dropped away from the valve block 15 so that the coned recess 5 is spaced from the coned valve seat and thus disconnecting the 110 compressors from the high and low pressure lines in which position of the cylinders the pistons may operate freely without compressing the fluid. Upon rotation of the 115 rotor at sufficiently high rate of speed the fly balls are, by centrifugal force, thrown outward and the lever ends 30 engaging the plate 29 raise the rotor causing the coned recess 5 to engage the coned end of the valve block in operative relation. By the shape 120 of these ends 30 of the fly ball arms and the thickness of the washer 29 the cylinder recess 5 may be made to engage with sufficient degree of force against the coned end 16 of the valve block to prevent a leakage of air 125 or gas between the coned faces.

The valve block 15 is a drive fit in the lower portion of the frame 19 and this portion is provided with channels 20 and 21 as shown in Fig. 4 registering with similar 130

channels 23 and 22 respectively in the valve block 15. Vertical channels 24 and 25 are provided on opposite sides of the axis of the shaft 4 opening respectively into the horizontal channels 22 and 23 of the valve block 5 and opening through the coned face of the valve block. This face of the valve block is provided with arcuate grooves 26 and 27 into which the channels 24 and 25 respectively 10 open. The ports 6, 7 and 8 of the cylinders register with these grooves 26 and 27 successively during the revolution of the cylinder block. These grooves are shown in dotted lines in Fig. 2.

15 Due to the eccentric relationship of the piston operating member 11 to the cylinder member, the piston in each instance begins to move outward on its intake stroke from the line *c* of Fig. 2. This movement is very slight and there is but little movement of the piston in the cylinder 2 in the position shown 20 in Fig. 2. However, whatever movement takes place is productive of slight vacuum in the cylinder end and approaches that of the vacuum or low pressure side 28 of the 25 circulating system connected with the intake channel 20. It will be seen in Fig. 2 that the port 7 of the cylinder 2 is about to open to the intake groove 27 of the valve block with which the intake line is connected through 30 the channel 25 of the valve block. Further outward movement of the piston in the cylinder, due to forward movement of the cylinder, draws in the charge from the intake line as the piston is turned about its center 35 practically to the position shown by the cylinder 3. Just as it reaches this position of the cylinder 3 the intake port of the cylinder passes from registration with the groove 27. Further movement of the piston in the direction shown by the arrow in Fig. 2 and, due to the eccentric relationship of the piston operating member 11, begins to 40 compress the introduced charge and, due to the spacing of the grooves 26 and 27, there is considerable movement of the piston raising the pressure of the fluid in the cylinder to that approaching the discharge line 29 connected with the exhaust channels 22 and 45 24 of the valve block. The port of the cylinder then opens to the groove 26 in communication with the discharge line 29 as stated, and continued inward movement of the piston forces the contents of the cylinder 50 into the discharge line. A check valve 99 should be provided in the discharge line to prevent a flow of any material volume of fluid into the cylinder chamber when the cylinder casting is moved away from the valve 55 block opening the ports. However, as the low pressure line, through the opening of the ports, is opened to the cylinder chamber and thus to the interior of the enclosing casing 80 of the unit, provision should be made 60 to take up this fluid and exhaust the same from the casing. This is particularly necessary in the case of transference of sulphur dioxide or other active gas, and this casing 80 is provided to prevent the leakage of gas into the room of a building in which the apparatus may be placed. This removal of gas from the enclosing casing 80 is accomplished by providing a pin hole 31 in the vacuum side of the system. This may be minute and the operation of the pump producing a vacuum in the line 28 tends to exhaust the gases from the chamber 80. As before stated, this is of moment in such cases as in refrigerating systems where gas is transferred from the low to the high pressure lines. In such instances there is necessarily a leakage in the chamber 80 when the intake valve is open through the dropping of the cylinder block away from the valve block. In artificial refrigerating systems there is an expansion valve between the high and the low pressure lines and if a check valve be provided as stated in the line 29, fluid under pressure in the line 29 beyond the check valve will, upon cessation of operation of the pump, become equalized if the coned recess 5 of the cylinder is open. By providing the pin hole intake in the low pressure line as described this gas is gradually exhausted from the chamber within the casing 80 upon succeeding operation of the compressor.

As heretofore stated, the piston operating member 11 turns about an axis eccentric to the axis of the cylinder block on the shaft 4. It is necessary for the desired nicety of operation that the piston member 11 should be turned simultaneously with the movement of the cylinder block and, if two members be driven constantly in the eccentric relationship stated, there is continued and successive reciprocable movement of the pistons in the respective cylinders. Preferably, the eccentric element 11 is driven by means of the cylinder block which is directly attached to the motor shaft 4. This may be accomplished in several ways as for instance by means of a pin 32 on the upper side of each cylinder extending into the circular aperture 33 which is considerably larger than the pin sufficient to allow for a relative movement of the pin in the aperture caused by the eccentric relationship of the parts. There are three cylinders here shown (although any number may be employed as desired) and thus at least one of the pins is in engagement with the forward edge or face of its aperture 33 as indicated in Fig. 5 and thus by rotation of the cylinder block the member 11 is caused to turn in unison therewith. Each pin 32 of the respective cylinders comes successively into driving relationship in the aperture of the member 11 and then passes out of driving relationship therewith, due to

the eccentricity of the parts as is indicated by the dotted circles within the aperture 33 shown in Fig. 5. By this means the member 11 is continuously driven through the successive engagement of the pins 32 of the several cylinders with the forward side of the respective apertures.

The design of the apparatus shown by the drawings is one particularly adapted for use with small household refrigerators for transference of the sulphur dioxide or similar refrigerant from low to high pressure lines, and the cylinders may be very small, about one inch in diameter and about five-eighths of an inch stroke, for the reason that being directly connected with the motor which has a relatively high rate of speed and while transferring a very small volume of refrigerant fluid at each stroke yet for any time interval the volume transferred is sufficiently large for the purpose.

The efficiency of the compressor is therefore as great as one having much larger cylinders and operated at the usual slow speed, and the efficiency is probably greater than that of the usual type of compressor handling an equal volume in the same period of time in view of the fact that practically no loss is occasioned as the pistons discharge practically the entire contents of the cylinders at each stroke.

From the foregoing description it is evident that the device is simple in construction, efficient in operation and is capable of being used directly connected with an electric motor by reason of the peculiar construction whereby the compressor is automatically loaded and unloaded permitting the motor to attain its running speed prior to the compressor assuming its load, and that the several objects of the invention are secured by the construction described.

Having thus fully described my invention, what I claim and desire to secure by Letters Patent of the United States is—

1. A fluid compressor comprising a series of radially positioned cylinders adapted for rotation about a common center, an eccentric ring like member rotatable about an axis eccentric to the axis of rotation of the cylinders, a piston for each cylinder, a piston rod connecting the piston to the eccentric ring, means for revolving the ring simultaneously with the cylinders, the cylinders each having a port near the inner end, a valve plate with which the inner ends of the said cylinders may seat, an intake and discharge conduit opening through the valve plate for registration with the cylinder port, and means whereby the speed of rotation of the cylinders may cause the cylinders and valve plate to assume co-operative relation.

2. In a fluid compressor, a series of radially positioned cylinders having the discharge ends adjacent the center and adapted

for rotation about the center, a reciprocable piston for each of the cylinders, an operating member rotatable about a center eccentric to the axis of rotation of the cylinders, a connecting rod between each piston and the eccentric member, means for rotating the said member and the cylinders at a common rate of speed to cause reciprocation of the pistons, there being intake and discharge conduits with which the discharge end of the cylinders may register in succession, and means whereby the speed of rotation of the cylinders causes the said conduits and discharge ends of the cylinders to assume co-operative relation.

3. In a fluid compressor, a series of radially positioned cylinders having discharge ends near the center and adapted for rotation about said center, a piston for each cylinder, a member rotatable about an axis eccentric to the axis of rotation of the cylinders with which the pistons are connected, means for rotating the said member and cylinders in unison, a valve plate, and intake and discharge conduits against which said discharge ends of the cylinders seat during revolution of the cylinders.

4. In a fluid compressor, a series of radially positioned cylinders having discharge ends near the common center and adapted for rotation about the center, the cylinders having a discharge conduit freely open to the cylinder, a valve plate, a seat for the plate at the cylinder ends, there being intake and discharge conduits formed on opposite sides of the plate and opening therethrough with which the ports of the cylinders register in succession during revolution of the cylinder, centrifugally controlled means for causing engagement of the valve plate and discharge ends of the cylinder an operating member rotatable about an axis eccentric to the axis of rotation of the cylinders and a connecting rod between the pistons and the operating member, the relationship of the pistons, operating member therefor and the valve plate conduits being such that the piston draws in a charge during registration of the cylinder port with the intake port and discharges the same during registration with the discharge port of the plate.

5. In a fluid compressor, a series of radially positioned cylinders each having an orifice providing an inlet and discharge port at the inner end, a valve plate having an intake port on one side and an exhaust port on the opposite side, intake and discharge lines connected with the respective valve ports, means for rotating the cylinders about the common center to bring the ports successively in registration with the intake and exhaust ports of the valve, centrifugally controlled means for causing the valve plate and ported ends of the cylinders to assume co-operative relationship, pistons for the

cylinders, and means for reciprocating the pistons in the cylinders in timed relation with the successive registration of the cylinder orifice with the intake and discharge ports of the valve.

6. In a fluid compressor, a series of radially positioned cylinders each having an orifice providing an inlet and discharge port at the inner end, a valve plate having an intake port on one side and an exhaust port on the other side, and a groove formed in the face thereof extending each way from each port, the ends of the grooves being spaced apart, intake and discharge lines connected with the respective valve ports, the cylinder ends being formed to provide a seat in which the valve engages during operation, centrifugally actuated means for causing engagement of the valve with the seat, means for rotating the cylinders about a common center to cause registration of each cylinder orifice successively with the grooves of the valve ports, pistons for the said cylinders, means for reciprocating the pistons in the cylinders in timed relation with the successive registration of the cylinder orifice with the intake and discharge ports of the valve, the piston movement being such that a partial vacuum is produced in each cylinder prior to registration of the cylinder orifice with the intake groove and the charge placed under pressure previous to registration of the orifice with the exhaust groove.

7. In a fluid compressor, a series of radially positioned cylinders having discharge ends near the common center, each cylinder having an orifice providing an inlet and discharge port at the inner end, there being provided a valve seat at said inner ends through which the orifices open, a valve block having an intake port on one side and an exhaust port on the opposite side, intake and discharge lines connected with the respective ports, rotation of the cylinders causing the orifice thereof to register successively with the intake and exhaust ports of the valve, centrifugally actuated means for causing engagement of the valve block with its seat, reciprocable pistons for the cylinders, a member rotatable about an axis eccentric to the axis of rotation of the cylinders, pivoted connecting rods extending between the pistons and the said member, said member being rotatable in unison with the cylinders to cause movement of the pistons in the cylinders in timed relation with the successive registration of the cylinder orifice with the intake and discharge ports in the valve.

8. In a fluid compressor, a series of radially positioned cylinders having discharge ends near the center and adapted for rotation about said center, a piston for each

cylinder, means for causing reciprocable movement of the pistons in the cylinder successively, each of the cylinders having an orifice providing an inlet and an exhaust port at the inner end, a valve seat through which the cylinder ports open, a valve plate having an intake and discharge orifice on opposite sides with which the cylinder ports may register in succession, a shaft to which the cylinders are attached, a motor directly connected with the shaft, and a centrifugally operated means for causing movement of the shaft to bring the cylinder ports and valve seat into engagement with the valve plate upon attainment of a certain speed of revolution and causing the cylinders and valve seat to become spaced from the valve upon reduction in speed of operation below said certain speed.

9. In a fluid compressor, an electric motor, a shaft to which the motor is directly secured, a pump comprising a series of cylinders directly connected to the said shaft, the cylinders each having an orifice providing an intake and discharge port, a valve seat through which the cylinder ports open, a valve having intake and discharge ports with which the cylinder ports are adapted to register in succession during operation, centrifugally operated means for causing the cylinder ports to assume operative relation with the valve member upon attainment of certain speed of rotation, pistons for the cylinders, and means for reciprocating the same in timed relationship with the registration of the cylinder ports with the valve ports.

10. In a fluid compressor, an electric motor, a shaft to which the rotor of the motor is directly connected, a series of radially positioned cylinders also directly connected with the shaft, the inner ends of which are each provided with an orifice, there being a valve seat through which the said orifices open, a stationarily positioned valve member having an intake and a discharge port on diametrically opposite sides, intake and discharge lines connected with the said ports, and centrifugally operated means for causing longitudinal movement of the shaft to bring the valve seat to engagement with the valve member upon certain speed of rotation of the shaft and to space the same upon a reduction in speed of operation of the motor.

11. In a self-loading and unloading fluid compressor, a cylinder having a port, a reciprocable piston, a valve having spaced intake and discharge ports with which the port of the cylinder registers successively, and a centrifugally operated means for causing the cylinder and valve to assume operative relationship upon attainment of certain speed of operation and to assume inoperative relationship upon cessation of such certain speed of operation.

12. A self-loading and unloading fluid compressor comprising in combination an electric motor, a shaft to which the rotor of the motor is directly attached, a rotary compressor directly attached to the shaft; a stationary valve member, intake and discharge lines opening through the face of the valve member, and centrifugal means operating upon attainment of certain speed to move the cylinders to operative relation with the valve member and permit disassociation of the cylinders with the said member upon certain reduction in speed.
13. A self-loading and unloading fluid compressor comprising in combination with a prime mover, of a vertical shaft to which the prime mover is connected, a series of radially positioned cylinders, the inner ends of which are provided with a port providing an inlet and discharge orifice, a valve seat at the said inner ends through which the ports open, the cylinder group being attached at the center directly to the shaft, a stationary valve member having an inlet and discharge port on opposite sides, the valve block being adapted to fit the said seat and the seat being normally spaced therefrom, centrifugally actuated means for moving the shaft longitudinally to cause engagement of the seat with the valve block upon attainment of certain speed of rotation of the cylinders, a reciprocable piston for each cylinder, and means for reciprocating the pistons in timed relation with the registration of the cylinder port with the intake and exhaust ports of the valve member.
14. A self-loading and unloading fluid compressor comprising the combination with a prime mover, of a vertical shaft to which the prime mover is connected, a series of radially positioned cylinders, the inner ends of each of which are provided with an orifice providing an inlet and discharge port, a valve seat at the said inner ends through which the ports open, the cylinder group being attached at the center directly to the
- 5 shaft, a stationary valve member having an inlet and a discharge port on opposite sides, intake and discharge lines for said valve ports, the said valve member being adapted to fit the seat and the cylinder block and seat being normally spaced from the valve and its ports, centrifugally actuated means for moving the shaft to cause engagement of the seat with the valve member upon attainment of certain speed of rotation, a reciprocable piston for each cylinder, a ring whose center is eccentric to the axis of rotation at the cylinders, a piston rod connecting each piston with the ring, and means for rotating the ring in unison with the cylinder block.
15. In a fluid compressor in combination with a prime mover, a shaft to which the prime mover is connected, a series of radially positioned cylinders attached directly to the shaft and rotatable therewith, the inner ends of the cylinders each having an orifice providing an intake and discharge port, there being provided a valve seat at the said inner ends through which the ports of the cylinders open, a stationarily positioned valve member having intake and exhaust ports on opposite sides, the said shaft extending through the valve member and movable longitudinally therethrough, centrifugally actuated means for causing movement of the shaft to bring the seat to engagement with the valve upon certain speed of rotation being attained, intake and discharge lines connected with the said ports of the valve, a closed chamber in which the cylinders are positioned into which the ports of the valve open when the parts are separated, there being provided a comparatively small aperture in the intake line within the said chamber whereby fluid discharged into the chamber on the opening of the valve ports thereto is withdrawn by the pumps when in operation.
- In testimony whereof, I sign this specification.

EARL P. OSWALD.
